TIRE

Armand V. Pedroso, Barberton, Ohio, assignor to The
B. F. Goodrich Company, New York, N.Y.

Filed Nov. 21, 1969, Ser. No. 20,217

Term of patent 14 years

Int. Cl. D12—14

U.S. Cl. D90—20

The figure is a perspective view of a tire showing my new design.

It is to be understood that the tread pattern continues as shown throughout the circumference of the tire, and the side opposite to the one shown is a mirror image thereof.

The characteristic features of the design reside in the tread and tread shoulder portions of the tire.

I claim:

The ornamental design for a tire, substantially as shown and described.
